MULTIFORM STATIONERY STRIP

Arthur H. Phillips, Hempstead, N. Y., and William Allan, Jr., Ridgefield Park, N. J., assignors, by mesne assignments, to American Sales Book Company, Inc., a corporation of Delaware

Application October 19, 1929, Serial No. 400,953

7 Claims. (Cl. 282—12)

This invention relates to printed paper forms of the multiplicate type, and is concerned more particularly with a plurality of continuous superimposed strips of successive forms printed in multiplicate and interleaved with carbon paper. 5 These strips are arranged so that their corresponding forms lie in registry to form a composite strip which is adapted to be passed through a typewriter or other printing apparatus for inscribing multiplicate data thereon, and after 10 being so inscribed the registering forms are separated from the composite strip in the form of complete sets of multiplicate data sheets.

Multiplicate form strips as heretofore arranged 15 tend to creep when passed through a typewriter or other printing machine, whereby the printing thereon is relatively displaced on the several multiplicate copies, and the operator must stop the machine frequently in order to rearrange the 20 strips in proper juxtaposition. Also, when these composite strips are handled the several individual strips tend to slip sidewise, and considerable care must be exercised in order to keep them together in proper relationship. Similarly, when 25 the sets of forms are being separated from the composite strip they tend to slip and become disarranged unless considerable care in handling is exercised.

It is the principal object of this invention to 30 obviate these objections to continuous multiform or composite stationery as now employed by securing the several strips together by fastening means not appearing upon the forms but on a border which is subsequently separable from the composite strip or from the separate sets of forms 35 after they have been inscribed with the record data.

More particularly, the invention comprehends a multiform strip or composite manifolding assembly having a border which is divisible from the composite form strip or from the separate sets of forms by tearing it off along a line of perforations through each separate strip or form, and a fastening means on or at this border serving to secure together all of the strips constituting the composite strip and being rendered ineffective to secure these strips together when the border is torn off. This border may be torn off before the composite strip is separated into the plurality of sets of multiplicate forms or form sheets, whereby the individual strips are released from each other, or the borders may be left on the several sets of multiplicate forms after they have been separated from the composite strips, whereby the separate forms are

held together in multiplicate to be jointly released as a set by tearing off the border or to be released separately by tearing them from the border one by one. Although the carbon paper which may be interleaved between the record or form strips may extend the full width of the strip and also include a perforated border secured by the fastening means to the borders of the other strips, it is preferred that the carbon paper be made narrower than the composite strip, 10 i. e., as wide as or slightly narrower than the forms exclusive of the separable border of the latter, so that the carbon paper may be withdrawn from between the forms before they are separated by tearing off their border, without 15 making it necessary to tear out the carbon paper from between the forms. Or the carbon or transfer strip or strips may terminate at their longitudinal edges opposite to their longitudinal attached margins somewhat short of the adjacent 20 longitudinal record strip edges so as to form a selective grip or selective grip formation whereby the marginal portions of the record strips may be gripped to the exclusion of the carbon strips. When the back of the form strips are carbonized, 25 the carbon paper is obviously eliminated and all of the strips have borders secured together by the fastening means.

Other characteristics and advantages of the 30 invention will be in part pointed out in the following detailed description of certain illustrative but preferred embodiments and will be in part obvious in connection therewith.

For a better understanding of this invention, reference is made to the accompanying drawing, 35 in which

Figure 1 illustrates a composite multiform paper strip interleaved with carbons and embodying this invention;

Fig. 2 is an enlarged partially diagrammatic 40 and exaggerated cross-section through the strip as seen along line 2—2 of Fig. 1;

Fig. 2a is an enlarged partially diagrammatic sectional view similar to that of Fig. 2 but showing a slightly modified structure;

Fig. 3 is a perspective partially diagrammatic view of the interfolded strip with the separable border partially removed; and

Fig. 4 is a perspective view of a set of multiplicate forms after separation from the composite strip but before the border is torn off.

In the drawing numeral 10 designates the continuous manifolding assembly or multiform strip of stationery consisting of a number of multiplicate strips of successive forms, each strip being 55

substantially like the other strips, except that the strips may vary in that different colors, different original printing, and different weights or grades of paper may be employed. As shown in Fig. 1, the individual strips making up the composite strip 10 are interleaved with carbon sheets 11 for the usual reason, although, if these strips are wholly carbonized or partly carbonized on their reverse surfaces the use of carbon sheets 10 11 is obviously not necessary.

The separate record and transfer strips making up the composite multiform strip 10 are provided with transverse lines of perforations 12, whereby the composite strip may be separated into a plurality of successive sets of multiplicate forms after the forms have been inscribed with record data by means of a typewriter or other printing machine, through which the composite strip is passed continuously, although, if desired, the sets 20 of multiplicate forms may be torn from the strip 10 before being separately inscribed with the record data. The carbon sheets 11 are also perforated transversely at a point coinciding with the perforations 12 in the form strips so as to be torn transversely at the same time, although, if desired, the carbon strips may be made unperforated so as to be withdrawn before the composite strip 10 is torn transversely into the separate sets of multiplicate forms, whereby the carbon 30 sheets 11 may be used over again.

As shown in the drawing, each of the strips included in the composite manifolding assembly or form strip 10 is provided with a continuous border 13 which is separable from the composite strip 10 by tearing along the longitudinal line of perforations 14 as shown in Fig. 3. If preferred, the sets 10' of interleaved record and carbon leaves may be first divided from the composite strip 10 before the border 13' is removed as shown in Fig. 4.

Although the carbon sheets 11 may be made the same width as the strips including their borders 13 as shown in Fig. 2a, and may be perforated longitudinally in the same way that the 45 paper strips are perforated as indicated at 14, it is desired for some uses of the manifolding assembly that the carbon sheets or strips 11 be made so as to have a width equal to or slightly less than the width of the paper form strips exclusive of the border 13 as shown in Figs. 1 and 2. In this way the carbon strips 11 are held in place by friction with sufficient security, and may be withdrawn after the forms are inscribed with the record data either before the sets of 50 forms are separated from the composite strip 10 by tearing the latter transversely along lines 12 into multiplicate sets, or after the composite strip 10 has been torn into its several sets of multiplicate forms as shown in Fig. 4.

In order to prevent creeping between the record strips and carbon strips or sheets 11 making up the composite strip 10 when this composite strip is passed through a typewriter or printing machine or is otherwise handled, and also to maintain the various strips or forms securely together, fastening means are provided on the border 13. These fastening means may be one of several known types, but the fastening means must not be bulky because they will interfere 65 with the free passage of the composite strip 10 through the printing machine. One form of fastening means consists of longitudinal stitching 15, as shown in Figs. 1 to 4, inclusive, this stitching being preferably applied in at least two places 70 on the border 13 of each set of composite forms

for the reason that when the forms are separated from the composite strip 10, as shown in Fig. 4, the multiplicate forms will not slip angularly relatively to each other and may be handled with impunity. Of course, if desired, only one 5 stitching 15 may be applied to the border 13 opposite each set of forms, which will be satisfactory if the border 13 is to be separated from the composite strip 10 before the composite strip 10 is divided into its several sets of multiplicate forms as shown in Fig. 3, or if a doubly secure fastening against relative movement between the forms is not necessary.

Another type of fastening means which has been found useful and satisfactory is also shown 15 in Fig. 1, and consists of a wire staple 16 which may be applied readily and is not bulky. Instead of using metal wire, a similar fastener may be made as also is shown at 17 in Fig. 1, this fastener consisting of thread passed twice through the 20 sets of forms and tied on the opposite side in the manner resembling the insertion of the wire staple 16.

Still another method of fastening the multiplicate strips or forms together comprises the use 25 of the paper itself when this paper is partially perforated and the cut portions passed through the several multiplicate sheets and folded back in the manner shown at 18 in Fig. 1. Here the several sheets are cut through in the form of a 30 V or semi-circle and the tongues or tabs thus formed are bent upwardly or downwardly or alternately upwardly and downwardly so as to secure the several strips together. It is preferred that these tongues be cut and bent in opposite 35 directions in the manner shown at 18 in Fig. 1, in order that relative movement between the multiplicate strips or forms is prevented in all directions.

Other suitable fastening means such as gluing 40 the edges of the borders 13 together or by employing spots of glue between successive borders of the several strips making up the multiplicate form 10 may be employed with equal facility.

In use, the composite strip 10, including the 45 unseparated border 13, may be readily handled in rolls or interfolded as shown in Fig. 3 along the transverse lines of perforations 12 without danger of relative creeping between the several strips making up the composite strip 10 and the carbon sheets 11, if these are employed. Thus the composite strip 10 may be passed through a typewriter or other printing machine without danger that the forms of each set will become disarranged, and that the data inscribed thereon 50 will become displaced on the several successive forms making up the multiplicate set. Also, after being so inscribed with the record data, the finished composite strips 10 may be handled in interfolded stacks as shown in Fig. 3, or in rolls 55 without danger that the record data will become disarranged or confused in any way.

When the inscription of the record data on the composite form strip 10 is completed, and it is desired to separate the strip into its successive 65 sets of multiplicate forms, it is only necessary to tear the strip 10 transversely along the transverse lines of perforations 12 in order to obtain the multiplicate sets of inscribed forms in secured relation as shown in Fig. 4, whereby they may 70 be individually handled without danger of disarrangement. In this form, shown in Fig. 4, the several separate forms may be removed one by one by tearing along the longitudinal line of perforations 14', or they may be released jointly by 75

tearing off the border 13' as indicated in Fig. 4. Alternatively, the border 13 may be torn off the composite strip 10 as indicated in Fig. 3 before the composite strip 10 is divided into its component sets of multiplicate forms.

When a set or unit of interleaved record and transfer sheets has been severed from the complete assembly as shown in Fig. 4 the carbons or transfer sheets may be quickly and easily separated from their interleaved relation with the record sheets after the binding margin 13' has been severed merely by grasping the projecting marginal portions of the record sheets to the exclusion of the carbon sheets, then giving the unit a quick jerk or swing whereupon the carbon sheets will be thrown out of the assembly unit. As shown at the right in Fig. 2 the records extend beyond the adjacent edges of the carbons thus providing a selective grip formation at each of the units of interleaved record and carbon sheets. In cases where the carbon strips 11 are extended at their longitudinal margins into the attached borders 13 so as to be attached in the assembly by the fastening devices 15, etc., as disclosed in connection with the embodiment of Fig. 2a, the method of separating the record and carbon sheets of a detached unit may be varied slightly. In the latter instance, the record and carbon sheets may either be detached one at a time as desired from the binding margin or borders 13', or the record sheets may be selectively gripped at the selective grip formation to the exclusion of the carbon sheets and thus severed along the weakened severance lines 14' from the attaching border, thus leaving the carbons attached to said border. The carbons may then be discarded and the record sheets or leaves distributed to the different departments or destinations as required.

It will be seen that in this way the several forms either in strips or separate sets, are fastened together securely without passing the fastening means through and consequently mutilating the multiplicate forms in any way, and without perforating the carbon sheets 11, if these are used. Consequently, the carbon sheets may be used again or may be readily withdrawn from between the form sheets without the need of tearing them out, or without destroying the carbon sheets.

The borders 13, after being torn off, may be destroyed, but, if desired, the top or bottom strip of this border may be inscribed with an index or other identifying data, either produced before the composite strip 10 or the severed set 10' is passed through the printing machine or when it is in the printing machine, this composite border thereafter serving as identifying the corresponding set of forms after the set of forms has been removed therefrom, or serving as a check stub, whereby the forms may be subsequently traced if misplaced or lost in a manner resembling the common use of check stubs.

While the multiform stationery strip described and shown herein has been shown in a few illustrative embodiments, it is to be understood that the invention is not limited thereby, but is susceptible of considerable variation in form and detail within its scope.

We claim:

1. Superposed record and transfer strips divided at intervals by transverse weakening lines to form sets of record sheets and interposed transfer sheets, the record strips only having each a longitudinal weakening line forming a detachable strip at overlying margins of such strips, the strips

being secured together at points within the boundaries of said detachable strips, and selective grip formations at free edges of each said set of sheets at points spaced from said detachable strips whereby the record sheets may be gripped to the exclusion of the transfer sheets.

2. Superposed record and transfer strips secured together along a marginal edge, the record strips only having longitudinal weakening lines adjacent to, and spaced inwardly from, the securing means, said strips having transverse weakening lines at intervals to form successive manifold sheet units, the transfer sheet or sheets of a unit having a marginal portion inwardly offset from the contiguous marginal edge of the record sheets to provide a selective grip formation.

3. Superposed record and transfer strips secured together along a marginal edge, the record strips only having longitudinal weakening lines adjacent to and spaced inwardly from the securing means, said strips having transverse weakening lines at intervals to form successive manifold units, the transfer sheet or sheets of each unit having a marginal portion at the edge opposite that at which the sheets of the unit are secured together inwardly offset from the marginal edges of the record sheets to provide a selective grip formation.

4. In a manifolding assembly, in combination, long continuous record and transfer strips interleaved in transfer relation, said assembly having longitudinally spaced transverse weakened severance lines whereby it may be divided into record units of interleaved record and transfer leaves, said record strips having longitudinally disposed weakened severance lines extending along one longitudinal assembly margin and transversely of said transverse severance lines to each said record unit so as to form a longitudinally disposed detachable binding margin for each said record strip at each side record unit, said binding margins of the respective record strips being relatively superposed, said record and transfer strips being attached together at said binding margins at each said record unit.

5. In a manifolding assembly, in combination, long continuous record and transfer strips interleaved in transfer relation, said assembly having longitudinally spaced transverse weakened severance lines whereby it may be divided into record units of interleaved record and transfer leaves, said record strips having longitudinally disposed weakened severance lines extending along one longitudinal assembly margin and transversely of said transverse severance lines to each said record unit so as to form a longitudinally disposed detachable binding margin for each said record strip at each said record unit, said binding margins of the respective record strips being relatively superposed, said record and transfer strips being attached together at said binding margins at each said record unit, said transfer leaves of said record units having, at points thereof spaced from said binding margin, edges inset from respective adjacent record leaf edges so as to provide selective grip formations respectively positioned at each said record unit.

6. In a manifolding assembly, in combination, long continuous record and transfer strips interleaved in transfer relation, said assembly having longitudinally spaced transverse weakened severance lines whereby it may be divided into record units of interleaved record and transfer leaves, said record strips having longitudinally disposed weakened severance lines extending along one

- longitudinal assembly margin and transversely of said transverse severance lines to each said record unit so as to form a longitudinally disposed detachable binding margin for each said record strip at each said record unit, said binding margins of the respective record strips being relatively superposed, said transfer strip or strips having longitudinal marginal portions overlapping said detachable binding margins of the record strips at each said record unit, and attaching means attaching said detachable binding margins of the record strips and said longitudinal marginal transfer strip portions together at each said record unit.
7. In a manifolding assembly, in combination, long continuous record and transfer strips interleaved in transfer relation, said assembly having longitudinally spaced transverse weakened severance lines whereby it may be divided into record units of interleaved record and transfer leaves, said record strips having longitudinally disposed weakened severance lines extending along one

longitudinal assembly margin and transversely of said transverse severance lines to each said record unit so as to form a longitudinally disposed detachable binding margin for each said record strip at each said record unit, said binding margins of the respective record strips being relatively superposed, said transfer strip or strips having longitudinal marginal portions overlapping said detachable binding margins of the record strips at each said record unit, attaching means attaching said detachable binding margins of the record strips and said longitudinal marginal transfer strip portions together at each said record unit, said transfer leaves of said record units having, at points thereof spaced from said binding margin, edges inset from respective adjacent record leaf edges so as to provide selective grip formations respectively positioned at each said record unit.
